UNITED STATES PATENT OFFICE.

FRANKLIN OSCAR DE HYMEL, OF SAN ANTONIO, TEXAS.

WATER-LIFT.

933,894.

Specification of Letters Patent. Patented Sept. 14, 1909.

Application filed May 2, 1908. Serial No. 430,443.

To all whom it may concern:

Be it known that I, FRANKLIN OSCAR DE HYMEL, a citizen of the United States, and a resident of San Antonio, in the county of Bexar and State of Texas, have invented 5 certain new and useful Improvements in Water-Lifts, of which the following is a specification.

My invention is an improvement in water lifts and consists in certain novel constructions and combinations of parts hereinafter described and claimed.

Referring to the drawings forming a part hereof Figure 1 is a central longitudinal section of the improved lift showing the piston in one position. Fig. 2 is a similar view showing the piston in another position. Fig. 3 is a central longitudinal section of the cylinder of the lift, Fig. 4 is a detail view 20 of the piston and disk valve, and Fig. 5 is a section on the line 5—5 of Fig. 4.

The present embodiment of my invention, 25 comprises a cylinder A, a casing B, a piston C, and a valve D.

The cylinder A is of equal cross section throughout, and is provided at its upper end, with an exterior annular flange a, provided at suitable intervals with openings, and the casing B is of greater diameter than 30 the cylinder, and is also provided with an exterior flange b at its lower end provided with openings adapted to register with the openings of the flange a when the casing is arranged coaxial with the cylinder, as shown 35 in Fig. 1, and bolts b' pass through the registering openings and are engaged by nuts b², whereby to secure the casing to the cylinder.

Since the casing is of greater diameter 40 than the cylinder, a shoulder a² is formed between the cylinder and the casing, the said shoulder being used for a purpose to be presently described. The piston C consists of a ring c, fitting snugly to the cylinder, and a spider c² is connected with the upper edge of the ring, the ring being shouldered as at c³, to permit the connection of the spider therewith. The spider is provided with a central bearing c⁴, in which is 45 threaded the lower end of the piston rod c⁵, and a piston valve c⁶ engages the top of the ring within the spider, said valve being retained in place thereby.

The disk D is provided with a central 55 opening d, through which passes the piston

rod c⁵, and the edges of the disk are adapted to rest upon the shoulder a² before mentioned, when the piston is on the down stroke. The casing B is provided with the usual outlet spout b³, and any suitable means 60 may be connected with the piston rod for operating the same.

In operation on the down stroke, the valve D will move down to its seat through the weight of the super-incumbent water, while 65 the piston valve will be raised by the water flowing into the cylinder. On the up stroke, the piston valve is closed by the weight of the super-incumbent water, and the water will be lifted by the piston raising the valve 70 D, and permitting the water to pass into the casing from whence it flows through the outlet spout.

It will be evident from the description, 75 that by drawing upward on the piston, all of the operative parts of the lift may be withdrawn from the well whereby to clean or repair the same with little trouble and but slight expense. This is of especial advantage, since it is not necessary to introduce a 80 separate cylinder into the well, the casing of the well acting as a cylinder.

It will be understood that the dimensions shown are not constant but may be varied in accordance with the end to be attained. In 85 deep water or oil wells, the cylinder will be of very small size and the other members of the lift reduced in accordance with formulas known to hydraulic engineers. For purposes of irrigation and in shallow wells the 90 cylinder will be of large size.

I claim:

1. A water lift comprising a cylinder of uniform interior diameter throughout adapted to be permanently placed in the ground, 95 a cylindrical casing of greater diameter than the cylinder and attached to the upper end of the cylinder, a piston having a valve located in the cylinder and attached to a rod extending through the cylindrical casing, 100 and a disk valve of greater diameter than the cylinder and of less diameter than the casing arranged in the casing and working loosely on the rod, substantially as described.

2. A water lift comprising a cylinder of uniform interior diameter throughout adapted to be permanently placed in the ground, an annular flange extending from the upper end of the cylinder, a cylindrical casing of greater diameter than the cylinder and at- 110

tached to the flange, a piston having a valve located in the cylinder and fitting closely therein and attached to a rod extending through the cylindrical casing, and a disk valve of greater diameter than the cylinder and of less diameter than the casing arranged in the casing and working loosely on

the rod, the disk valve being adapted to seat on the upper end of the cylinder, substantially as described.

FRANKLIN OSCAR DE HYMEL.
